UNITED STATES PATENT OFFICE.

ALFRED F. MASURY AND ROBERT S. BOLGER, OF NEW YORK, N. Y., ASSIGNEES TO
INTERNATIONAL MOTOR COMPANY, OF NEW YORK, N. Y., A CORPORATION OF
DELAWARE.

CLUTCH CONTROL DEVICE.

1,345,685.

Specification of Letters Patent.

Patented July 6, 1920.

Application filed July 2, 1918. Serial No. 242,993.

To all whom it may concern:

Be it known that we, ALFRED F. MASURY and ROBERT S. BOLGER, citizens of the United States, and respectively residing in the 5 borough of Manhattan and in the borough of Queens, of the city of New York, in the State of New York, have invented certain new and useful Improvements in Clutch Control Devices, of which the following is a 10 specification, reference being had to the accompanying drawings, forming a part hereof.

This invention has particular relation to the application of an internal combustion engine to a use in which, under certain conditions, the speed of the engine should be controlled automatically by a governor while, under other conditions, higher engine speed is required without the necessity for 15 governor control. Such a use, for example, is that to which an engine is applied when it furnishes the power for a readily transportable search-light and may be employed at one time in driving the generator of the 20 search-light apparatus and at another time in driving the truck upon which the search-light and engine are mounted for the purpose of changing the location of the search-light. In accordance with the invention 25 there are provided means, usually embodied in some form of clutch and therefore referred to hereinafter, for convenience, as a clutch, between the governor and its driving means, whereby the governor can readily be 30 connected to or disconnected from its driving means. The invention will be more fully explained hereinafter with reference to the accompanying drawings in which it is illustrated, and in which—

40 Figure 1 is a detail view, partly in elevation and partly in section, illustrating particularly the relation of the governor, its driving means, and the interposed clutch, a portion of the engine also being shown.

45 Figs. 2 and 3 are detail views, on a larger scale of the clutch device.

In Fig. 1 of the drawings there is shown an internal combustion engine which may be of any desired type indicated generally 50 at e .

The governor, indicated generally at g and of suitable construction, is adapted to control, through suitable linkage g' , the throttle valve e^2 of the engine so as to regu-

late the speed of the engine. In the arrangement shown in the drawings this governor is driven from the crank shaft e' of the engine through suitable gearing, indicated at g^2 and g^3 . The vertical shaft, by which the governor is directly driven, has two independent parts g^4 and g^5 , adapted to be connected by an interposed clutch device, shown generally at h and comprising, in the construction shown, a circumferentially grooved sleeve member h' suitably connected with the 55 shaft member g^4 and notched, as at h^2 , to engage the toothed end g^6 of the shaft member g^5 . An operating lever h^3 is suitably mounted in the casing h^4 , its end projecting through a cam slot k' in an operating and locking plate k which is pivotally mounted, as at k^2 , on the casing h^4 .

When the locking and controlling plate k is swung to the right, in Fig. 2, the clutch sleeve h' is raised and held out of engagement with the shaft member g^5 , so that the governor is then disconnected from its driving means, while if the locking and controlling plate k is swung to the left, the clutch sleeve h' is moved into engagement with the 75 shaft member g^5 so that the governor is then driven from the engine shaft and operates in the usual manner to control the speed of the engine.

It will be obvious that the invention may 80 be applied to engines and governors of different forms and that the construction in which it is embodied may be varied in each instance to suit the conditions of use.

We claim as our invention:

The combination with an internal combustion engine, of a governor to control the speed thereof, gearing and a two-part shaft whereby the governor is driven from the engine shaft, a separable clutch interposed between the two parts of the two-part shaft and including a grooved sleeve member, an operating lever engaging said sleeve member and a manually operable pivoted operating and locking plate having an eccentric cam 95 slot with which said lever is engaged whereby the sleeve is held in or out of driving relation to the two parts of the shaft.

This specification signed this 29th day of June, A. D. 1918.

ALFRED F. MASURY.
ROBERT S. BOLGER.
